UNITED STATES PATENT OFFICE.

WASHINGTON I. PHIFER, OF COLLINSVILLE, ILLINOIS, ASSIGNOR OF ONE-FOURTH TO
JULIAN F. BENTLEY, OF EDWARDSVILLE, ILLINOIS.

ENGINE.

1,006,269.

Specification of Letters Patent. Patented Oct. 17, 1911.

Application filed October 17, 1910. Serial No. 587,367.

To all whom it may concern:

Be it known that I, WASHINGTON I. PHIFER, a citizen of the United States of America, residing at Collinsville, in the county of Madison and State of Illinois, have invented certain new and useful Improvements in Engines, of which the following is a full, clear, and exact description, reference being had to the accompanying drawings, forming part of this specification.

This invention relates to engines having pistons reciprocable under pressure derived from any suitable fluid which is introduced into cylinders within which said pistons are operated, and has for its primary object to provide an improved construction, combination and arrangement of parts in devices of this character.

One of the objects of this invention is to provide an improved construction according to which an engine of this character may be simply and economically manufactured and rendered durable and efficient in operation.

Other and further objects will appear in the specification and be specifically pointed out in the appended claims, reference being had to the accompanying drawings exemplifying the invention and in which,

Figure I is a longitudinal section through my engine. Fig. II is a vertical cross section taken on line II—II, Fig. I. Fig. III is a side elevation of the cam wheel carried by the engine shaft. Fig. IV is an edge view of the cam wheel. Fig. V is a cross section through the cam wheel, taken on lines V—V, Figs. III and IV.

Inasmuch as my engine is designed to be operated by fluid motive power of different descriptions either in the nature of an explosive agent, or steam, for example, I do not in the accompanying drawings show means for delivering the motive power to the cylinders of the engine, nor the valves or other appurtenances by which the delivery and discharge of the motive power to and from the engine is controlled. Such elements may be any of those ordinarily used, as will be readily appreciated upon an understanding of the device to which my invention relates.

In the drawings: 1 designates the shell of my engine, this shell being closed at its ends by cylinder heads 2, through which the

motive power to be used in the engine is admitted and discharged.

3 designates cylinders arranged in batteries within the shell 1 at the ends thereof, and which abut against the cylinder heads 2, one battery of cylinders appearing most clearly in Fig. II, while the location of the cylinders longitudinally of the shell is shown in Fig. I. The cylinders in each battery are parallel with each other, and are connected by spider arms 4 extending radially from a central hub 5. The space around the cylinders, which are separated from each other, as seen in Fig. II, is closed at the outer end of each battery by the adjacent head 2, and such space is closed at the inner end of each battery by a suitable wall, thereby providing a water jacket chamber A, making it possible to prevent overheating of the cylinders in which pistons operate, as will hereinafter more fully appear. Each cylinder 3 of the engine is closed at its outer end, except for inlet and exit ports, by the adjacent head 2, while the inner ends of the cylinders are in open communication with a central chamber B.

6 designates pistons operable in the cylinders 3 and movable through the open inner ends of said cylinders. These pistons are arranged in pairs longitudinally of the engine so that a piston in one of the batteries mates with a piston of the other battery, and the pairs of pistons are united by connecting bars 7, each of which is supplied with an anti-friction roller 8.

9 designates a shaft extending longitudinally of the engine, and rotatably fitted in the shell heads 2 and the hubs 5 disposed centrally of the batteries of cylinders. This shaft extends through the central chamber B and it has fixed to it a cam wheel 10. The cam wheel 10 is disposed diagonally of the shaft 9 so that during its rotation its side face will, at different points, approach and recede from the inner ends of the cylinders 3. In the rim of the cam wheel is a helical runway 11 in which the anti-friction rollers 8, carried by the piston connecting bars 7, operate.

In the practical use of my engine, the pistons upon their forward strokes carry with them the connecting bars 7, uniting the pistons in pairs longitudinally of the engine, and during such forward strokes of the pistons, the anti-friction rollers 8 by bearing

against the inclined walls of the helical runway 11 in the cam 10 act upon said cam to cause rotation thereof, with the result of imparting rotary movement to the shaft 9, 5 by which the cam is carried. It will be appreciated that, due to the runway in the cam being a helical one, either wall of the runway therein against which an anti-friction roller 8 bears recedes at the point of bearing 10 touched by the anti-friction roller, and that the roller naturally tends to move in the direction of recession of such runway wall. And it is due to this fact that power is transmitted from a piston to the cam and 15 the shaft carrying it. It is obvious that while any given piston is operating in the manner stated to drive the cam on the engine shaft, the piston mating with the drive piston works idly during its backward 20 stroke in so far as power action by the shaft is concerned, and it will be apparent that when the idle piston has completed its backward stroke, it is ready in its turn to perform the office of imparting a reverse movement to the connecting bar 7 attached to 25 it for the operation of the cam 10 in the same manner as such office was previously performed by the piston at the other end of the engine. I prefer to employ six cylinders 30 and six pistons in each battery of such pistons and cylinders, this being the number illustrated in the drawings, but it is evident that the number of cylinders and pistons may be other than that shown without de- 35 parting from my invention.

The essential characteristic features in my engine in so far as the operation of the engine shaft by the pistons is concerned, are the provision of the cam wheel on the engine 40 shaft having a runway or track-way face arranged obliquely relative to the shaft, and means to which power is communicated in the operation of one or more pistons to the runway or track surface to cause rotation of 45 the cam wheel and engine shaft by travel of the means referred to along the runway or track surface.

The chamber B in my engine, in which the cam 10 operates, is intended to be supplied 50 with a quantity of oil in which the cam moves during its rotation. The oil present in this chamber is continually agitated by the cam, and as a result of a limited degree of heat radiating from the cylinders, the oil 55 is in a measure vaporized so that it will be rendered a most perfect lubricant which is constantly delivered to the working parts of the engine operating in the chamber B. This lubricant, upon being caught by the 60 pistons, is transferred from them to the interiors of the cylinders 3 without there being any waste of lubricant, and without any opportunity of mixture of dirt or foreign matter with such lubricant. Moreover, 65 the presence of the oil bath in chamber B,

providing as it does a continuously renewed coating to the exterior surfaces of the pistons 6, effectually checks any tendency of the pumped fluid forcing its way past the pistons from chambers 3 into the chamber B. 70

The water jacket chambers A serve, as previously mentioned, to prevent overheating of the cylinders and the pistons operating in them, and I make use of water delivered into these chambers for swabbing the interior walls of the cylinders upon each stroke of the piston, by producing in the walls of the cylinders, ducts 12 (see Fig. I), that lead to the interiors of the cylinders, and provide the pistons with annular grooves 80 6' that receive water from said ducts when the grooves are brought into registration therewith. In this manner, rings of water are caused to be constantly present in the annular grooves in the pistons, which act with cooling effect upon the internal faces of the cylinders, assisting in lubrication of such faces, and further serve as packing rings between the pistons and the internal faces of the cylinders. 90

The herein described construction and arrangement of parts, adapts the engine to develop a maximum amount of power by reason of the large leverage of action upon the engine shaft, due to the connecting bars 95 7 being disposed on the walls of the pistons farthest from the engine shaft, with the periphery of the cam 9 running between the oppositely disposed pistons.

I claim:

1. In an engine, the combination with an outer shell, of batteries of cylinders disposed at opposite ends of said shell with an oil containing space between said batteries, a shaft rotatable on an axis centrally disposed with respect to said cylinders, a cam keyed to said shaft in said oil space, said cam having its outer periphery extending around said shaft in a plane inclined thereto and the outer peripheral face of said cam being provided with a runway, a hollow cylindrical piston reciprocable in each cylinder, a connecting member for each pair of oppositely disposed pistons, said member being secured to the inner cylindrical walls 110 of said pistons, and an antifriction roller carried by said connecting member and running into said runway.

2. In a device of the character described, the combination with a cylindrical shell open at both ends, of a battery of cylinders disposed within each end of said shell, said cylinders in each battery being provided by tubular openings extending entirely through said batteries, cover plates for said shell, said cover plates also forming the outer ends of said cylinders and having inlet ports for said cylinders, a hollow piston reciprocable within each cylinder, a connecting bar secured to the inner walls of oppositely dis- 125 130

- posed pistons whereby they are caused to move in unison, an antifriction roller on each of said connecting bars, a shaft journaled in said batteries of cylinders, a cam 5 keyed to said shaft and provided in its peripheral face with a runway extending obliquely around said shaft, said runway being in running contact with the roller on said connecting rod.
- 10 3. In an engine of the character described, the combination with a cylindrical shell open at both ends, of an integral member disposed in each open end of said shell, said members leaving a free space adjacent the 15 longitudinal center of said shell, and each of said members being provided with a plurality of cylindrical openings extending therethrough, said openings being arranged in oppositely disposed pairs, cover plates for said shell, said plates being adapted to form 20 covers for the outer ends of said cylinders and having port openings therefor, pistons reciprocable within said cylinders, a connecting bar for connecting each pair of oppositely disposed pistons, a shaft centrally 25 disposed with respect to said cylinders, a cam keyed to said shaft and having a runway in its peripheral face extending obliquely around said shaft, and a roller mounted on each of said connecting bars and 30 in running engagement with said runway.

WASHINGTON I. PHIFER.

In presence of—
JULIAN F. BENTLEY,
GEORGE DEUTSCH.
